UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

BOLT GUIDE.

Application filed February 2, 1926. Serial No. 85,552.

This invention relates to sliding bolts for securing or locking doors, casement windows, and the like in closed position.

More particularly, the invention resides in 5 a guide or staple for slidably supporting the bolt.

An aim of the invention is to provide a staple of this character which is very neat and trim in appearance. My improved 10 staple is relatively narrow, being only slightly wider than the bolt which it supports and being devoid of lateral projections. The means, such as screws, for securing the staple in place is concealed from view by the 15 bolt.

A further object of the invention is to provide a staple or guide for the bolt which is characterized by its extreme simplicity in construction, its economy in manufacture, 20 and its strength and durability. A staple constructed in accordance with the present invention is formed from sheet metal by relatively few and simple operations, and the arrangement is such that the screws 25 which secure the staple in place hold the staple in proper formed condition.

Other objects will be in part obvious and in part pointed out more in detail herein-after.

30 The invention accordingly consists in the features of construction, combination of elements and arrangement of parts which will be exemplified in the construction herein-after set forth, and the scope of the application of which will be indicated in the appended claims.

In the accompanying drawings:

Figure 1 is a view of a pair of my improved staples supporting a bolt;

40 Fig. 2 is a transverse sectional view taken on line 2-2 of Fig. 1;

Fig. 3 is a top view of my improved staple;

Fig. 4 is a bottom view thereof;

45 Fig. 5 is a perspective view of the staple; and

Fig. 6 is a view of a blank from which the staple is constructed.

Referring to the drawings in detail, *a* denotes a bolt of suitable construction; *b*, my improved guides or staples for slidably supporting the bolt; and *c*, the usual strike plate. The bolt may be carried by a door or the sash of a casement window or the like, 55 and the strike plate is carried by the casing

or frame in the usual manner. The bolt, in the present illustrative disclosure, is half round in cross section, that is to say, semi-cylindrical.

Referring now more particularly to my improved guide, the same has an elongated base portion 10, an ear 11 at each end of the base portion, and a bridge portion 12 curved correspondingly to the curved surface of the bolt. The bridge or arch arises from, and is 60 formed integral with, the side edges of the base. The ears 11 may be provided with openings 13 to receive fastening means, such as screws 14, and which screws, when the bolt is in place, are concealed by the bolt. 65 The base is diagonally slit, as at 15, one ear being joined to the metal to one side of this slit, and the other being joined to the metal to the other side of the slit. 70

My improved guide may be formed from 75 a blank of sheet metal, such as shown in Fig. 6. This blank may be stamped to the configuration shown, and has an intermediate portion 12^a which, when the blank is bent to form, constitutes an arch. At opposite 80 sides of this intermediate portion are oppositely disposed triangular portions 10^a which are adapted to form the base 10. The edges 15^a of the portions 10^a are in parallelism with each other so that, when the blank is 85 bent into semi-circular shape, these edges meet to form the slit 15. At diametrically opposite corners of the blank are the ears 11 which, preferably, project, as at 17, 90 slightly beyond the inclined edges 15^a. 90

It will be noted from the foregoing description, taken in connection with the accompanying drawings, that my improved guide or staple may be manufactured at a very low cost, since the staple is constructed 95 of sheet metal and but two operations, each of which may be cheaply carried out, are necessary in constructing the staple, these operations being that of stamping from sheet metal a blank to the configuration 100 shown in Fig. 6, and then rolling the blank into semi-cylindrical form. In case the openings or holes 13 are to be countersunk, as shown, the countersinking operation may be very readily carried out. 105

The completed staple is relatively narrow and, in fact, extends beyond the side edges of the bolt only that distance substantially equal to the thickness of the metal of which the blank is formed. The staple is 110

substantially of uniform width throughout its length, and the screws 14 are positioned behind, and are obscured from view by, the bolt. This means that the staple is very 5 slightly and trim, a feature of considerable importance in hardware of this sort. The staple is very strong and rigid and, since the ears are respectively integral with the two portions of the base, and the slit 15 is 10 diagonally disposed, the screws 14 maintain the staple against lateral spreading and distortion.

As many changes could be made in the above construction and many apparently 15 widely different embodiments of this invention could be made without departing from the scope thereof, it is intended that all matter contained in the above description or shown in the accompanying drawing shall 20 be interpreted as illustrative and not in a limiting sense.

It is also to be understood that the language used in the following claims is intended to cover all of the generic and specific 25 features of the invention herein described and all statements of the scope of the invention which, as a matter of language, might be said to fall therebetween.

I claim as my invention:

30 1. A staple for sliding bolts formed of sheet metal and having a base with a slit, a single ear extending from each end of said base, and an arch arising from and formed

integrally with the side edges of said base; one of said ears being integral with the 35 metal of the base to one side of said slit, and the other ear being integral with the metal of the base to the other side of said slit each of said ears being of substantially the same width as the staple and extending 40 longitudinally of the base.

2. A staple for sliding bolts formed from a blank of sheet metal rolled into semi-cylindrical shape and having a flat base with an apertured ear at each end and a diagonally 45 extending slit where the side edges of the rolled blank meet, and a semi-cylindrical arch integral with the side edges of said base between said ears each of said ears extending in the longitudinal direction of the 50 staple and being within the limits of the side edges of the staple.

3. A staple for sliding bolts having a flat base portion with an ear at each end, and a bridge portion integral with the side edges 55 of said base portion between said ears, said base portion having a slit extending diagonally substantially from one side edge to the other side edge thereof, said ears being substantially as wide as said base portion 60 and being respectively integral with the metal to opposite sides of said slit, each of said ears extending longitudinally of the base and being within the limits of the side edges of the base.

STUART W. PARSONS.
